NUTATING MECHANISM

Joseph I. Herzlinger, Oaklyn, N. J., assignor to
Radio Corporation of America, a corporation
of Delaware

Application June 26, 1946, Serial No. 679,336

7 Claims. (Cl. 74—87)

1

This invention relates to improvements in mechanisms for effecting a change in the axis of a rotating body and will be described as applied to a system wherein the rotating body moves an antenna of a radar or like installation.

In certain ultra-high frequency "pulse" systems for the communication of intelligence, notably in so-called "target-tracking radar" and analogous (position determining) systems, it has heretofore been proposed to employ a hollow rod-like member or "wave guide" as the antenna and to subject the said member to nutation, selectively, at a small angle, a large angle or a spiral between the two angles, for purposes of electrically exploring or "scanning" the ether.

The mechanisms employed for selectively imparting such precessional movements to an antenna have heretofore been more complex and cumbersome than is desirable in apparatus designed for use in air-craft and other mobile installations.

Accordingly, the principal object of the present invention is to provide a reliable yet simple automatic means for nutating an antenna, selectively, at a small angle, a large angle or a spiral between the two angles, and one which dispenses with the complicated clutches and relays heretofore employed in effecting the change-over.

The foregoing and other objects are achieved in accordance with the invention by the provision of a novel centrifugally controlled mechanism which operates, in response to a change in speed of the driving motor, to effect the desired precession or change in the orientation of the axis of the driven member.

The invention will be described in connection with the accompanying drawing wherein:

Fig. 1 is a longitudinal view, partly in section of a motor driven nutating antenna system incorporating a centrifugally actuated mechanism, within the invention, for controlling the angle of nutation.

Fig. 2 is a similar view, with the motor omitted, showing how the centrifugal control of the invention operates to increase the angle of nutation or cone of precession of the antenna and

Fig. 3 is a fragmentary view of the centrifugal control and including a gear system and switch for continuously varying the displacement of the axis of precession of the antenna.

As previously indicated the purpose of the mechanism shown in Figs. 1 and 2 is to nutate the movable antenna or wave guide A about a point P at a small angle θ such as 1 degree (Fig. 1) and,

2

selectively, at some large angle ϕ (Fig. 2) such as 6 degrees. As will hereinafter more fully appear this "precession" or change in the direction of the axis $x-x$ of the movable antenna A is achieved by changing the speed of the motor M from, say, 1800 to, say, 900 revolutions per minute.

(Having regard to the electro-mechanical target-tracking problems involved it is usually expedient to use the higher motor speed in achieving the smaller angle of nutation.)

As is conventional, the hollow-rod-like antenna A is supported adjacent to its inner end upon a gimbal consisting of a ring or sleeve 2 in which the antenna can turn on an axis through the diameter of the ring, while the ring itself is so pivoted on a tiltable support, indicated generally at 4, that it can turn about a diameter at right angles to the first mentioned diameter. As is likewise conventional, the pulses or high frequency energy to be broadcast by the antenna A are supplied thereto by a stationary wave guide 6 having a convex outlet port (or "choke joint") 6a which abuts the similarly curved inlet port 8a of the antenna without interfering with the nutation of the latter.

It will be observed that the gimbal ring or sleeve 2 within which the antenna is mounted is provided with an integral extension 10 which terminates in a bushing 12 within which a shaft 14 is journaled for rotation. Since the part 10 is integral with the gimbal ring 2 and is supported only on the tiltable support 4 it is apparent that any force applied to the outer (i. e. left) end of the shaft 14 which results in movement of its axis of spin (so that the said axis traces a cone of precession about point P as the apex) will subject the antenna A to nutation so that it too traces a cone, the apex of which is the point P.

(It should be noted that the antenna does not spin about its axis when subject to the described force, because the rotary movement of the driven shaft 14 is not transmitted beyond the bearing 12 within which the said shaft is journaled. The movement to which the antenna A is subjected can best be visualized by holding a mechanical pencil at its point, in the left hand, with the clip on the pencil toward the observer and then, with the right hand, moving the free end of the pencil in a circle, keeping the clip facing the observer at all times, and the left hand stationary.)

The apparatus of Figs. 1 and 2, as thus far described is of a known type and the present invention is not concerned with the foregoing details of construction except in so far as the said

apparatus is capable of being driven by the novel centrifugally controlled mechanism herein described. This mechanism comprises a bell crank assembly comprising two levers 16 and 18 joined at one end by a pivot 20 and pivotedly connected at their fulcrums, 16a and 18a to the shaft 22 of motor M. As shown more clearly in Fig. 1 the motor shaft 22 is hollow and has a rod 24 mounted for axial movement within its bore. It is normally biased to the left, as viewed in Fig. 1, by a spring 26 which exerts its force against a piston 28 on the said end of the rod. The piston 28 and its spring 26 operate within an oil-filled cylinder 30 so that the assembly comprises a dash-pot which damps the later described axial movement of the rod 24. The cylinder 30 is threaded on, or otherwise affixed to, the motor shaft 22 and hence rotates therewith. Suitable stops 32 and 34 within the shaft 22 limit the degree of axial movement of the rod 24 with respect to the said shaft.

The opposite end of the axially movable rod 24 is connected by a short link 36 to the pivot 20 which joins the adjacent ends of the two levers 16 and 18. The free end of one of the levers, i. e. lever 16, is provided with a bearing in the form of a stub-shaft or pin 38 which is slideably splined for axial movement in the bifurcated end of the tiltable driven shaft 14 which is supported by the gimbal 2 upon which the antenna A is mounted. The free end of the other lever is provided, in accordance with the invention, with a counterweight 40.

The center of gravity of the nutating system controlled by the counterweight 40 is at the point T on the side of the axis of rotation (x-x) which is opposite to the counterweight 40. In order to fix this center of gravity at the indicated point the rotatable nutating shaft 14 is weighted as indicated at 14a, on the side opposite the counterweight 40.

The operation of the apparatus of the invention is as follows: When the motor M is driven at its higher speed (e. g. 1800 R. P. M.) the sum of the moments of the counterweight 40 about the fulcrum 18a of the lever 18 and the moment of the nutating mass about the fulcrum 16a of the other lever 16, exerts a force at the central pivot 20 which is greater than the biasing force of the spring 26 acting on the piston 28. Hence, the piston rod 24 moves to the right, as shown in Fig. 1, to a position whereat its axial movement is arrested by the stop 32. This axial movement of the rod 24 is applied by the link 36 to the lever 16 so that the said lever pivots counterclockwise on its fulcrum 16a. Thus the stub shaft or pin 38 on the outer end of this lever 16 applies a tilting force to the driven shaft 14 and the said shaft exhibits a slight (say, 1 degree) nutant or nodding movement about the point P. As previously set forth, this change in the orientation of the axis of the driven shaft 14 with respect to the fixed axis of rotation of the driving shaft 22 is transmitted by the gimbaled support 2 to the antenna A which thus exhibits the same small angular degree of nutation about point P, as the said shaft 14.

In order to increase the angle of nutation of the driven shaft 14 (and hence to increase the diameter of the cone traced in space by the antenna A) it is merely necessary to operate the motor M at its second or lower speed, in this case 900 R. P. M. When the speed of the motor is thus reduced the force of the spring 26 is greater than the centrifugal force exerted by the counter-

weight 40 and the nutating mass 14 and A, hence the rod 24 is pulled against the right hand stop 34. As shown in Fig. 2 this movement of the rod 24 to the left pulls the pivot 20 in the same direction and imparts a clockwise movement to the bell crank 16 and the desired additional degree of tilt to the driven shaft 14. It may be pointed out that the system stays in dynamic balance at both speeds, and during the change-over, since the center of gravity T and the counterweight 40 move in the same direction with respect to the axis of rotation of the driving shaft 22.

When it is necessary or expedient to change the angle of precession, continuously, between the small angle of Fig. 1 and the large angle of Fig. 2, suitable means may be provided for changing the speed of the motor M. Thus, as indicated in Fig. 3, the speed of the motor may be controlled by a switch 42 under the control of a cam 44 which is driven by pinion 46 on the motor shaft 22 through a driven gear 48 on the cam shaft 50. Here the counterweight 40 operates, as before, to nutate the driven shaft 14 at a small angle at the higher motor speed and at the larger angle at the lower speed. Hence, when the speed of the motor is changed, periodically, the free end of the antenna will describe a spiral, between the said angles, in space.

It will now be apparent that the present invention provides a reliable yet simple centrifugal means for nutating an antenna, or other rod like structure, selectively, at a small angle, a large angle, or a spiral between the two angles.

What is claimed is:

1. In apparatus of the character described, a driving shaft mounted for rotation about a fixed axis, a driven member mounted to permit of nutation about a point substantially in register with said axis, means connecting said shaft and said member in driving relation, and centrifugal means responsive to the speed of rotation of said driving shaft for controlling the angle of nutation of said driven member.

2. The invention as set forth in claim 1 and wherein said driven member comprises a rotatable shaft.

3. The invention as set forth in claim 1 wherein said driven member comprises a rod-like antenna and wherein said connecting means between said driving shaft and said antenna includes a nutant driven shaft.

4. In apparatus of the character described, a driving shaft mounted for rotation at different speeds about a fixed axis, a driven shaft having an axis of rotation and mounted to permit of changes in the orientation of its said axis with respect to said fixed axis, means connecting said shafts for rotation about their respective axes, and centrifugal means responsive to said different speeds of said driving shaft for changing the orientation of said axis of said driven shaft with respect to said fixed axis.

5. The invention as set forth in claim 4 including means for periodically changing the speed of rotation of said driving shaft, whereby the axis of said driven shaft generates a cone of precession in changing its orientation with respect to said fixed axis.

6. In apparatus of the character described, a hollow rotative driving shaft containing a rod-like member mounted for axial movement therein, a plurality of bell-cranks pivotedly connected each at one end to one end of said axially movable rod and each at its fulcrum to said driving

shaft, a driven shaft supported at one end for nutation and connected at its opposite end in torque transfer relation with respect to said driving shaft through one of said bell-cranks, and a counterweight carried by the other of said bell-cranks and responsive to rotation of said driving shaft for moving said rod-like member axially whereby to apply a nutating force to said driven shaft through the other of said bell-cranks.

7. The invention as set forth in claim 6 and wherein the center of gravity of said driven shaft is diametrically opposite said counterweight.
